DESIGN FOR A SIGN

Paul Hess, Chicago, Ill., assignor to Panellit Displays Inc., Chicago, Ill., a corporation of Illinois

Application December 3, 1934, Serial No. 54,231

Term of patent 7 years

To all whom it may concern:

Be it known that I, Paul Hess, a citizen of the United States, residing at Chicago, Illinois, have invented a new, original, and ornamental Design for Signs, of which the following is a specification, reference being had to the accompanying drawing, forming part thereof.

The dominant features of my design reside in the parts shown in full lines on the drawing.

I claim:

The ornamental design for a sign, as shown and described.

PAUL HESS.
